CONTACT CARRIER

Harry A. Douglas, Bronson, Mich.

Application November 25, 1932, Serial No. 644,281

3 Claims. (Cl. 173—328)

This invention relates to contact carriers more particularly for electrical circuits.

Among other objects, the invention aims to provide novel, economical and efficient assembly means for the carrier and current conducting elements carried thereby.

Other objects and advantages will be apparent from the following description taken together with the accompanying drawing showing an illustrative embodiment of the invention.

In the drawing—

Figure 1 is a longitudinal sectional view of one form of structure embodying the invention, parts being shown in elevation, and dotted lines indicating other structures with which the invention may be employed;

Figure 2 is a section somewhat reduced, taken on the line 2—2 of Figure 1, and being an end view of the carrier;

Figure 3 is a perspective view of the carrier shell alone, also somewhat reduced; and

Figure 4 is a view similar to Figure 1 but showing a modified structure incorporating the invention.

The illustrative carrier is inclusive of a cylindrical metallic shell 1 having a rear wall 2 perforated as at 3. The forward end of the shell is open to receive a contact carrying plug such as the lamp base 4 shown in dotted lines, the lamp base having the usual bayonet pin 5 thereon which is received in a bayonet channel 6 in the shell 1, thus fixing the insulated contacts 7, carried by the plug 4, rotatively of the shell 1. This forward end of the shell 1 which receives the plug 4 is desirably bent back upon itself to form an integral cylindrical skirt portion 8 which is substantially uniformly spaced from the shell 1 to overlap the bayonet channel 6, but at the same time to provide clearance for the bayonet pin 5 between the shell 1 and a support for the shell such as the socket 9, also shown in dotted lines, which may yieldingly grip the skirt portion 8. The socket 9, as is well known, may be itself attached to a suitable mounting and may thus support both the plug 4 and the contact carrier.

The shell 1 carries an insulating block here shown as a fiber disc 10 abutting the rear wall 2 of the shell 1 and secured thereto as by having longitudinal extensions of the shell such as the integral ears 11 bent back over the disc as best shown in Figure 2. To fix the rotative position of the disc 10 with respect to the shell the disc may be provided with notches to receive the extensions 11, here represented by the spaces 55 between the pairs of ears 12 and 13, the ears of

a pair being sufficiently spaced apart to snugly receive one of the extensions therebetween.

The disc 10 is perforated in registry with the perforation 3 in the rear wall of the shell, in this instance as by the perforations 14. As shown in Figure 1, the perforations 14 have fixed therein hollow rivets 15 which are rearwardly extended as at 16. The rivets 15 are arranged in parallel and are so located by the perforations 14 as to be each longitudinally aligned with one of the contacts 7 carried by the block 4.

In accordance with my invention, each of the rivets 15 slidably receives a metallic sleeve 17. As shown in Figure 1, the sleeve 17 is formed integrally with a contact 18, and the wire 19 having the usual insulation 20 thereon is passed through the sleeve 17 and into the bore 21 of the contact, the insulation being stripped from the wire 19 where it terminates in the bore of the contact and the sleeve 17 encasing the insulation 20 for a portion of its length. The wire 19 is permanently secured to the sleeve 17 and contact 18 by having the contact swaged as at 22, preferably at more than two places, to reduce its bore as at 23, distorting the wire 19 thereabouts and forming interengaging shoulders between the wire and bore which firmly unite the parts together. The sleeve 17 at its rear end is flanged as at 24 to provide an annular shoulder at one end of the sleeve and the contact 18 is radially enlarged as at 25 to provide another annular shoulder, these shoulders limiting movement of the sleeve and contact in the rivet 15. The shoulder 24 may be formed on the sleeve 17 after the sleeve, with the wire therein, has been passed rearwardly through the rivet 15, thereafter the parts being normally inseparable. The contact and sleeve however are urged forwardly to cause the contact to engage one of the complementary contacts 7 by a coil spring 26 disposed annularly about the sleeve and compressed between the disc 10 and the shoulder 25.

Referring to the modification shown in Figure 4, the rivets 27 instead of being themselves longitudinally extended each slidably receives therein the sleeve 28 which is separable from the contact 29. In this case, the sleeve 28 is flanged at its forward end as at 30 and at its rearward end as at 31 to provide annular shoulders limiting movement of the sleeve. The contact 29 is swaged to the wire 19a in the same way as in Figure 1, but in this case is separable from the sleeve 28 so that the contact 29, wire 19a and insulation 20a are all slidably received in the sleeve 28. The contact 29 being radially en-

larged as at 32 abuts the shoulder 30 to limit movement of the contact and wire rearwardly, the contact and wire being pressed forward by the coil spring 33 which is compressed between 5 the disc 10 and the shoulder 30. Thus the carrier may be assembled at the factory separably from the wire and contact 29, which may be later inserted in the sleeve 28 by being passed rearwardly through the sleeve until the shoulder 32 of the contact abuts the shoulder 30 of the sleeve as described.

It will be understood that when there is no lamp base 4 or other such plug inserted in the forward end of the shell 1, that the contacts described carried by the shell, are urged forward by the springs 26 or 33 as the case may be until the shoulders at the rear ends of the sleeves 17 or 28 abut their respective rivets. Obviously, in the case of the Figure 1 structure, the contact 18 itself serves to hold the spring 26 in place, while in the Figure 4 structure, the spring 33 is held in place by the shoulder 30 of the sleeve 28 even when the contact 29 is removed.

Having described my invention, I claim:

25 1. A contact carrier embodying a cylindrical metallic shell portion having a rear wall, the

body thereof being struck up to form oppositely disposed ears in prolongation of the shell side wall and cut out therebetween to form oppositely disposed similar semi-circular perforations, in combination with a contact carrying disc of insulating material having oppositely disposed pairs of outstanding ears adapted to snugly receive between each pair one of the rear wall prolongations of the shell and clamped against the said rear wall by the ends of said prolongations bent into engagement with the exterior thereof. 10

2. The structure of claim 1 wherein the disc is provided with oppositely disposed perforations concentric with the end wall perforations for reciprocably mounting contacts extending within 15 the interior of the shell.

3. The structure of claim 1 wherein the disc is provided with oppositely disposed perforations concentric with the end wall perforations for reciprocably mounting contacts extending within 20 the interior of the shell including a spring pressed sleeve within each perforation and about each contact to extend the respective contacts within the shell.

HARRY A. DOUGLAS. 25
